By Carl M. Sinclair, M.D.

UNITED STATES PATENT OFFICE.

FRANK O. PETERSON, OF FORT DODGE, IOWA, ASSIGNOR, BY MESNE ASSIGNMENTS, TO
PEOPLES INVESTMENT COMPANY, A CORPORATION OF SOUTH DAKOTA.

BURGLARPROOF LOCK.

Application filed August 18, 1924. Serial No. 732,593.

An object of this invention is to provide improved auxiliary means for locking a vault or safe door.

5 A further object of this invention is to provide improved means for suspending the locking function of the auxiliary locking means.

10 A further object of this invention is to provide improved means for applying the locking function of the auxiliary locking means through the use of heat, explosive or impact force such as might be applied by a burglar improperly attempting to unlock the doors.

15 A further object of this invention is to provide improved means for preventing locking of a vault door in closed position by an authorized and uninstructed person.

20 A further object of this invention is to provide improved means for enabling an occupant of a vault to prevent reopening of a door which has been closed and attempted to be locked by an unauthorized and uninstructed person.

25 A further object of this invention is to provide a dead-lock whereby the auxiliary locking means of a vault door may itself be locked, which dead-lock is suspendible or operable to unlocking position by means applied to the inner face of the door only.

30 A further object of this invention is to provide means for removing, discharging and suspending the locking operation of the auxiliary locking means of a vault door which shall be operable and susceptible of use from the outer face of the door.

35 My invention consists in the construction, arrangement and combination of elements hereinafter set forth, pointed out in the claims and illustrated by the accompanying drawing, in which—

40 Figure 1 is an inner face elevation of a vault door of common construction showing my improved devices mounted thereon as required for practical use. Figure 2 is an inner face elevation of the auxiliary locking means, partly in section, and other devices carried thereby and usable for preventing unauthorized locking of the door and for 45 authorized locking of the door at the inner face thereof. Figure 3 is a top view, partly in section, of the devices shown in Figure 1 and Figure 4 is a bottom view of the same devices. Figure 5 is a cross-section on the indicated line 5—5 of Figure 2. Figure 6

is a vertical section on the indicated line 6—6 of Figure 1. The elements are shown in Figures 2 to 6 inclusive on a larger scale than the showing in Figure 1.

50 Figures 7 and 8 are details showing a modified form.

This invention relates to protective means for safe and vault doors. It is common practice for burglars to gain admission to the locking mechanism and effect an opening of a vault door by several methods, some of which are burning a hole in the door and cutting the dogging bar through said hole by means of a torch, or drilling through the door into the lock case and manipulating 65 or destroying the lock tumblers by force, or blowing the lock case and operating means therein off of the door by an explosive charge applied thereto, or driving the lock case inwardly from the door by impact on the 70 exterior of the door. All of these and other methods render impotent and susceptible of unauthorized manipulation, the locking bars of the door and permit access to the interior of a vault by opening of the door. Part of 75 my improvements relate to the provision of an auxiliary locking mechanism normally held out of operation by retaining means, which retaining means are released or suspended by and through the medium of any 80 method of forcing the door above set forth or any other method using heat, impact or explosive to destroy or permit unauthorized access to the lock case or dogging bar. The auxiliary locking mechanism when released 85 and put into operation effectively prevents manipulation of the locking bars of the door and may be so located as to be substantially inaccessible to and not susceptible of manipulation by an unauthorized person when the 90 door is closed.

95 It sometimes occurs that a robber forces the guardian of the vault or safe into the same and confines him by closing the door and locking the mechanism thereof. Some 100 of my improvements are designed to prevent the locking of the door by the robber when he has confined the guardian in the vault. Taken alone these elements of security might react to permit the robber to reopen the door 105 and assault or otherwise dispose of the guardian of the vault and to prevent such occurrence other of my improvements relate to means whereby the occupant of the vault can so lock the door that the robber cannot 110

reopen it. This arrangement tends to the security of the occupant of the vault and gives him courage and opportunity to communicate with persons outside, such as police officers, as by telephone communication from the interior of the vault.

In the construction of the device as shown the numeral 10 designates the face plate or body of a vault door of common and ordinary construction, which plate is provided with hinge members 11, inner flanges 12, 13, locking bars 14 slidingly mounted in said flanges and extending transversely of the door in parallel spaced relation, a carrying bar 15 mounted on and connecting the locking bars 14 between said flanges, other locking bars, supports therefor and bell cranks connected thereto, a lock case 16 and a dogging bar 17, all of which are common and well known and are here used conventionally to demonstrate the mounting and operations of my improved elements. A supporting bracket 18 is mounted in a horizontal position parallel with and spaced from the inner face of the door plate 10 and extends transversely of the carrying bar 15 between said carrying bar and the door plate; one end portion of said bracket abutting the inner face of the flange 13; the bracket being secured by a cap screw 19 extending through a hole formed therefor in the flange 13 and seated in and longitudinally of the bracket. A locking block 20 is pivoted on the barrel of a shouldered screw 21 extending through said block and screw-seated in and transversely of the bracket 18, the smaller end portion of the shouldered screw projecting slightly from that face of the bracket 18 adjacent to the door plate 10. The shouldered screw 21 is formed with a transverse slot in each end thereof whereby a screwdriver may be applied to remove the screw from the bracket. When it is desirable, as hereinafter will appear, to remove the screw 21 from the exterior when the door is closed, a hole is drilled or burned in the plate 10 in registration with the smaller end portion of said screw and a screwdriver is introduced through said hole and employed to drive the screw out of its seat in a direction away from said door plate. One end portion of the locking block 20 is curved and relatively smooth and a hook 22 is located near the opposite end thereof and on the upper side margin of the block. A flange 23 is formed on the upper marginal portion of the locking block 20 and extends across the plane of and above the bracket 18 and said flange is beveled at one end and is adapted to engage the upper margin of the bracket and limit oscillation of the block in one direction, the flange itself being adapted to lie at times on the upper margin of the block and limit oscillation of the block relative to the bracket in one direction. The

opposite end face of the locking block 20 also is curved throughout the major portion of its length and is formed with ratchet teeth or serrations 24 extending transversely of said end face, a portion 25 of the end face 70 remaining plane. A tubular handle 26 is fixed at one end to the bracket 18 and is arched upwardly therefrom and across the flange 23 of the locking block, the opposite end portion of said handle being secured to one end of an end plate 27 which extends across and projects beyond the flush and otherwise free end of the block 18 and is secured thereto. The tubular handle 26 is formed with a slot 28 on its concaved side and an arm 29 on the adjacent end of the flange 23 extends through said slot and substantially across the bore of the handle. An expansive coil spring 30 is mounted loosely in the tubular handle 26 and impinges at one end on a closed end portion of said handle and at the other end of a ball 31, which ball in turn contacts with one face of the arm 29. It is the function and tendency of the spring 30 to hold the locking bar 20 in operative position with the flange 23 resting on the bracket 18 as shown by dotted lines in Figure 2 and other means about to be described are employed to hold said locking block in open position as shown by solid lines and suspended as to its locking functions against expansion of said spring. A recess 32 is formed in the bracket 18 and opens to the plane between the locking block and bracket and a recess 33 is formed in the locking block 20 and is adapted to register with the first recess when the locking block is in operative position as shown by dotted lines in Figure 2. A hole 34 is formed in the locking block 20 and affords communication between the outer face of the locking block and the recess 33, which hole is of less diameter than the recess. An expansive coil spring 35 is mounted in the recess 32 and a tumbler 36 also is mounted in said recess and is adapted to compress said spring at times, being held by the spring in such position that it lies partly in the recess 32 and partly in the recess 33 and serves as a dead-lock between the locking block 20 and bracket 18. The dead-lock can be suspended by being moved out of the recess 33 wholly into the recess 32 through manipulation (endwise pressure) of a key 37 placed through the hole 34. The functions of the dead-lock are suspended at times when the locking block is in inoperative position such as is shown by solid lines in Figure 2 and become effective immediately and automatically when the locking block assumes the position shown by dotted lines in Figure 2.

A plate 38 is mounted across the inner face of the lock case 16 and is adapted to transmit any jar or impact applied to the lock case from the opposite side of the door

plate 10. An angle bar 39 is fixed to the inner face of the door plate 10 below the lock case 16 and another angle bar 40 is mounted adjustably thereon and has one arm extending across the central portion of and spaced from the plate 38. The two angle bars 39 and 40 are adjustably connected to compensate for differences in thickness of lock cases 16 and such adjustment is effected by means of bolts 41, 42 extending through a slot 43 in one arm of the bar 40 and through holes in one arm of the bar 39, the slot being of materially greater length than the distance of separation of the bolts. Contacting faces of the adjacent arms of the bars 39 and 40 preferably are serrated to lend stability to the adjustable connection between them. The long arm of the bar 40 is formed with a notch 44 in its extremity, which notch lies in a plane parallel with the plane of the plate 38. A trigger 45, substantially U-shaped and with one arm longer than the other, is mounted loosely in and extends through the long arm of the bar 40. The long arm of the trigger 45 extends into end-wise contact with the central portion of the plate 38 while the short arm of said trigger extends across the notch 44. A leaf spring 46 is mounted on the bar 40 and overlies and impinges at one end on the closed end or portion of the trigger 45. An anchor 47, preferably composed of two lengths of wire connected by a fusible link 48, is fixed at one end to the flange 13 at a point opposite the lock case 16 and said anchor is attached at its other end to the hook 22 on the locking block. The anchor 47 is of such length that when the locking block is in inoperative position the bight of the anchor can be placed within the notch 44 and be retained therein by the short arm of the trigger 45, in which position the anchor holds the locking block in inoperative position against expansion of the spring 30. The location of the locking block 20 when in inoperative position is such that the carrying bar 15 is permitted a full degree of movement to and fro between said block and the adjacent flange 13. However when the door is closed and the carrying bar and locking bars are moved to locking position to any extent up to the limit of the range of movement of the carrying bar that way, the locking block 20 when released from or by the anchor 47 will move into engagement with the carrying bar (except as hereinafter noted) and through the medium of its serrated face, contacting with said carrying bar, prevent any opening or unlocking movement until such time as the locking block is turned again manually into its inoperative position. The application of heat by a torch to such degree as to burn a hole through the door plate 10 into the lock case or to expose the dogging bar would raise the temperature of the fusible link 48 sufficiently to open it and thereby sever the anchor 47 and permit the auxiliary locking means (the locking block 20) to be thrown 79 into locking position. Or, any impact applied to the exterior of the door plate 10 or any explosive force applied to the lock case in an effort to gain access to the lock case or to separate it from the door plate 75 would react through the plate 38 on the long arm of the trigger 45 to the end of moving said trigger against the pressure of the leaf spring 46 sufficiently to release the bight of the anchor from the trigger; which 80 done, the locking block would be moved into operative and locking position by expansion of the spring 30. In the event that the carrying bar is at the innermost limit of movement when the locking block 20 moves to 85 operative locking position, a space exists between the plane portion 25 of the adjacent end portion of the locking block and the adjacent side margin of the carrying bar as illustrated by dotted lines in Figure 2, 90 said dotted lines showing the carrying bar at both limits of movement illustrative of this condition. When the locking block attains to its operative position the deadlock becomes effective as above noted. 95

A hole is formed in the lower projecting end portion of the plate 27. A lever 49 is pivoted on a screw 50 seated in the lower margin of the block 18 contiguous to the flange 13, and said lever is formed with a right-angled flange 51 at one end, which flange is formed with a transverse hole registering with the hole in the plate 27. A rock-shaft 52 is extended through and journaled in the holes in the plate 27 and flange 51, a right-angled arm 53 is formed on one end of said rock-shaft adjacent to the flange 13 and an expansive coil spring 54 is mounted loosely on said rock-shaft between said arm and the flange 51. The opposite end portion of the rock shaft 52 is threaded and an adjusting nut 55 is mounted thereon outside of and adapted to contact with the plate 27. It is the function of the adjusting nut 55 to fix and determine the degree of separation 100 of the arm 53 and flange 51 under expansion of the spring 54 to compensate for slight variations in the mounting of the bracket due to different thicknesses of flanges 13, 105 because in some instances it is necessary to shim the bracket relative to the flange to obtain a correct location therefor. The threaded end portion of the rock-shaft 52 is bent at right angles substantially in the same direction as the arm 53 thereby forming a handle 56 by means of which the rock-shaft can be manipulated. The inner end portion of the lever 49 is bent downwardly to form a handle or lug 57 and a shoulder 58 is formed on one side margin of said lever 110 115 120 125 130

by means of a long tapering notch 59 formed therein. The rock-shaft 52 extends across the handle 57 between said handle and the door plate 10 and said handle is reduced in 5 width relative to the body of the lever for such purpose.

In the practical use of the devices last above described, when the vault door is opened for any purpose the rock-shaft 52 is oscillated by turning the handle 56 from a depending position into a horizontal position directed toward the door plate 10 and the friction created by the spring 54 will hold it in such position. This movement of the 10 rock-shaft 52 turns the arm 53 into a position between the flange 13 and the adjacent margin of the carrying plate 15 where it will prevent movement of the carrying plate to the extreme of locking arrangement. Hence, 15 when the door is closed by an unauthorized person such as a robber and the normal locking mechanism is shot toward locking position, it will be stopped short of the extreme 20 of movement in that direction and in such 25 position that the normal combination lock devices or tumblers cannot be operated to lock the elements so located. At this time an occupant of the vault would manually move the handle 57 in a direction away from 30 the door plate 10, thus placing the shoulder 58 at the rear of the rear face of the carrying bar 15, thereby preventing the carrying bar being moved again to open or unlocking 35 position. It is to be expected that the robber upon discovering that he is unable to turn the combination and lock the door shut might attempt to reopen the door to make other disposition of the occupant of the vault and it is to prevent this that the shoulder 58 is 40 provided on the lever 49.

When the arm 53 is properly located to prevent the door being locked by the combination and the lever 49 has been manipulated to prevent the carrying bar being 45 placed in open position, the occupant of the vault is in security and may await relief from the exterior with composure or turn to auxiliary means such as a telephone provided in the vault to give an alarm and summon 50 aid.

In Figures 7 and 8 I have shown a modified form in which the lever 49 is omitted, together with its function. In lieu thereof a lug 49' is rigidly secured to the lower face 55 of the block 18 by means of a screw 50', and is formed at one end with a downturned flange 51' which is apertured to provide a bearing for the rock shaft 52, against which flange the spring 54' has a bearing 60 as before. The lug 49' is also formed with a marginal flange 49'' which projects up past one edge of the block 18 to prevent turning of said lug.

I claim as my invention—

65 1. Auxiliary means for locking a vault or

safe door which door is provided with a carrying bar, comprising a bracket mounted on the door and extending across said bar, a locking block arranged on one side of and pivoted to said bracket in the plane of movement of said bar, yielding pressure devices carried by the bracket and adapted to move the locking block into contact with said bar, trigger released means adapted to hold said locking block at times out of contact with 70 said bar, and a dead-lock carried by the bracket and adapted to engage and lock the block to the bracket at times.

2. Auxiliary means for locking a vault or 80 safe door, which door is provided with a carrying bar, comprising a bracket mounted on the door and extending across said bar, a locking block arranged on one side of and pivoted to said bracket in the plane of movement of said bar, the end face of the locking block adjacent to said bar being curved and serrated throughout the major portion of its curve, yielding pressure devices carried by the bracket and adapted to move the locking block into contact with said bar, trigger released means adapted to hold said locking block at times out of contact with 85 said bar, and a dead-lock carried by the bracket and adapted to engage and lock the block to the 90 bracket at times.

3. Auxiliary means for locking a vault or 95 safe door, which door is provided with a carrying bar, comprising a bracket mounted on the door and extending across said bar, a locking block arranged on one side of and pivoted to said bracket in the plane of movement of said bar, yielding pressure devices carried by the bracket and adapted to move the locking block into contact with said bar, trigger released means adapted to hold said locking block at times out of contact with 100 said bar, the end portion of the locking block farthest from the bar being curved and adapted to be engaged by said trigger released means, and a dead-lock carried by the bracket and adapted to engage and lock the 105 lock to the bracket at times.

4. The combination with a vault door having a lock case, locking bars, a carrying bar and a dogging bar, of an auxiliary locking device carried by said door and adapted to engage at times with said carrying bar, an adjustable angle bracket mounted on said door and extending over said lock case and formed with a notch in its extremity, a trigger mounted in and extending through the notched end portion of said bracket, one arm of said trigger extending into proximity with the lock case, and a flexible anchor attached at one end to the locking device and at the other end to said door, the bight of said anchor extending at times through the notch in said bracket and engaged by said trigger.

5. The combination with a vault door hav-

ing a lock case, locking bars, a carrying bar and a dogging bar, of an auxiliary locking device carried by said door and adapted to engage at times with said carrying bar, an 5 adjustable angle bracket mounted on said door and extending over said lock case and formed with a notch in its extremity, a plate interposed between the notched end portion of said bracket and the lock case, a trigger 10 mounted in and extending through the notched end portion of said bracket, one arm of said trigger extending into proximity with said plate, and a flexible anchor attached at one end to the locking device and 15 at the other end to said door, the bight of said anchor extending at times through the notch in said bracket and engaged by said trigger.

6. The combination with a vault door having 20 a carrying bar, of a bracket mounted on said door and extending across said carrying bar, auxiliary locking means carried by said bracket and adapted to engage said bar at times, and means carried by said bracket 25 adapted for manual adjustment into a position to limit movement of the carrying bar toward locking position at times.

7. The combination with a vault door having 30 a flange and bolt work movable in a plane transversely thereof, of a supporting bracket mounted on said flange and extending across said bolt work, means mounted for oscillation on a horizontal axis and adapted to be moved manually to a position between 35 said flange and bolt work whereby the movement of the bolt work relative to said flange and toward locking position is limited.

8. The combination with a vault door having 40 a flange and bolt work movable in a plane transversely thereof, of a supporting bracket mounted on said flange and extending across said bolt work, means mounted for oscillation on a vertical axis and adapted to be moved manually to a position whereby it 45 may be engaged by a portion of the bolt work and limit the movement of the same toward locking position.

9. The combination with a vault door having 50 a flange and bolt work movable in a plane transversely thereof, of a supporting bracket mounted on said flange and extending across said bolt work, means mounted for oscillation on a vertical axis and adapted to be moved manually to a position whereby it 55 may be engaged by a portion of the bolt work and limit the movement of the same in one direction, and means mounted for oscillation on a horizontal axis and adapted to be moved manually to a position between 60 said flange and bolt work whereby the movement of the bolt work relative to said flange in one direction is limited.

10. In a device of the class described, a 65 bracket formed with a recess, a locking block arranged on one side of and pivoted to said

bracket, said locking block being formed with a recess adapted to register with the first recess at times, a spring-backed dead-lock mounted in the first recess and adapted to enter the second recess at times, said 70 bracket being formed with a keyhole communicating from its exposed side to the latter recess and adapted to receive a key whereby the dead-lock may be operated to release from the locking block. 75

11. In a device of the class described, a bracket, a locking block arranged on one side of and pivoted to said bracket, said locking block being formed with a flange on its upper margin extending across said 80 bracket, an arm extending from said flange, yielding pressure devices acting on said arm in one direction, and means attached to said block for holding the same against said pressure. 85

12. In a device of the class described, a bracket, a locking block arranged on one side of and pivoted to said bracket, said locking block being formed with a flange on its upper margin extending across said bracket, a 90 hook on said flange, and an anchor attached to said hook and adapted to hold said block against said pressure at times.

13. In a device of the class described, a bracket, a locking block arranged on one 95 side of and pivoted to said bracket, said locking block being formed with a flange on its upper margin extending across said bracket, one end portion of said flange being beveled and adapted to contact with said bracket and limit movement of the block in one direction, an arm extending from said flange, yielding pressure devices acting on said arm in one direction, and means attached to said block for holding the same 100 against said pressure. 105

14. In a device of the class described, a bracket, a plate extending across and secured at one end to said bracket and projecting therefrom at both ends, a tubular 110 handle carried by said bracket and plate, an expansive coil spring in said handle, a locking block arranged at one side of and pivoted to said bracket and formed with a flange extending over said bracket, an arm on said flange extending within and adapted for travel longitudinally of said tubular handle, said arm being engaged by said spring, and a hook on said flange adapted 115 to be engaged by an anchor. 120

15. In a device of the class described, a bracket, a rock-shaft mounted on said bracket and formed with an arm at one end, a spring interposed between said arm and its bearing, and a handle formed on the 125 opposite end of said rock-shaft.

16. In a device of the class described, a bracket, a rock-shaft mounted on said bracket and formed with an arm at one end, a spring interposed between said arm and 130

its bearing, an adjusting nut mounted on said rock-shaft, and a handle formed on the opposite end of said rock-shaft.

17. In a device of the class described, a bracket, a lever fulcrumed on said bracket and formed with an apertured ear at one end, a plate mounted on said bracket and formed with an apertured end portion registering with said ear, a rock-shaft journaled in the apertures of the ear and end portion, said rock-shaft being formed with an arm at one end, an expansive coil spring interposed between said arm and the ear, an adjusting nut mounted on the opposite end of said rock-shaft and adapted to engage said apertured end portion of the plate, and a handle formed on said rock-shaft adjacent said adjusting nut.

18. In a device of the class described, a bracket having a notch in one end, a yoke-shaped trigger traversing said notched end, one arm of the trigger extending across said notch and spaced from the bottom thereof.

19. In a device of the class described, a bracket having a notch in one end, a yoke-shaped trigger traversing said notched end, one arm of the trigger extending across said notch and spaced from the bottom thereof, and a leaf spring mounted on said bracket and engaging the closed end portion of the yoke-shaped trigger.

Signed at Fort Dodge, in the county of Webster and State of Iowa, this 30th day of June, 1923.

FRANK O. PETERSON.
